Kevin Prince(57) **CLAIM**

I claim the ornamental design for a bale feeder, as shown and described.

DESCRIPTION

FIG. 1 is a perspective view of a bale feeder, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a magnified partial left-side elevation view thereof, taken along line 8 of FIG. 4; and,

FIG. 9 is a magnified partial bottom plan view thereof, taken along line 9 of FIG. 7.

The broken lines showing horses and hay in FIG. 1 depict environmental matter and form no part of the claimed design.
